UNITED STATES PATENT OFFICE.

C. H. PLATT, OF NEW YORK, N. Y.

SHIP'S BLOCK.

Specification of Letters Patent No. 8,950, dated May 18, 1852.

To all whom it may concern:

Be it known that I, C. H. PLATT, of New York, in the county and State of New York, have invented a new and useful Improvement 5 in Blocks for Ships; and I do hereby declare that the following is a full, clear, and exact description of the same, reference being had to the annexed drawings, making a part of this specification, in which—

10 Figure 1, is a side view of the block. Fig. 2, is a vertical section taken at the line X, X, Fig. 4. Fig. 3, is a transverse vertical section of the lower parts of the cheeks, the metal hoops or bands being also bisected, 15 this view shows the grooves in the peripheries of the cheeks in which the hoops or bands fit. Fig. 4, is an end view of the upper portion of the block, showing the bolt which passes through the eyes of the hoops 20 or bands and secures the cheeks the proper distance apart at the upper end of the block.

Similar letters of reference indicate corresponding parts in each of the several figures.

The nature of my invention consists in 25 encompassing the cheeks of the block with metal hoops or bands which fit in grooves in the peripheries of the cheeks. Said hoops or bands being bent at the upper end or part of the block so as to form eyes through 30 which a bolt passes which secures the cheeks the proper distance apart at the upper end.

To enable others skilled in the art to construct blocks upon my improved plan, I will proceed to describe fully the manner of construction. 35

A, represents the cheeks which are circular, each cheek has a groove (a) see Fig. 3, in its periphery, in which a metal hoop or band B, fits, these hoops or bands are bent 40 at the upper part of the block so as to form eyes C, C, through the eyes a bolt D, passes, the eyes fitting in recesses near the ends of the bolt, the bolt it will be seen secures the cheeks the proper distance apart at the upper end as the hoops or bands fit in the 45 grooves in the peripheries of the cheeks. E,

is a metal plate at the lower end or "arse" of the block, the plate has grooves stamped in it corresponding to the grooves around the cheeks, and the convex surfaces on the 50 under side of the plate formed by the grooves in the outer side fit in the grooves in the peripheries of the cheeks, the hoops or bands also fit in the grooves in the plate, see Fig. 3, binding it firmly to the cheeks 55 and keeping them the proper distance apart at the bottom or "arse" of the block. F, is the sheave or pulley. G, is the hook attached to and turning loosely on the bolt D.

The metal hoops or bands are shrunk on 60 the cheeks. The hoops or bands may fit in the grooves about as far as represented by the dotted lines in Figs. 1, and 2.

By employing the hoops or bands as herein shown the cheeks are prevented from 65 splitting, the rope is also prevented from wearing or chafing the cheeks on their inner sides, by forming the eyes in the hoops at the upper part or end of the block and employing the bolt, no plate is required to connect the cheeks at their upper ends and consequently a larger sheave may be used with given sized cheeks, than can be used in blocks as at present constructed. 70

I do not claim the metal plate E, for connecting the cheeks, for that has been previously employed; but 75

What I claim as new and desire to secure by Letters Patent, is—

The employment or use of the metal bands 80 or hoops B, said hoops or bands encompassing the cheeks A, and fitting in grooves (a) in the peripheries of the cheeks, the hoops or bands having eyes C, C, formed in them at the upper end of the block through which 85 the bolt D, passes securing the cheeks the proper distance apart at the upper end of the block as set forth.

CHAS. H. PLATT.
